HYDRAULIC PUMP OR MOTOR

Walter Ernst, Mount Gilead, Ohio, assignor to
The Hydraulic Press Corporation, Inc., Wil-
mington, Del., a corporation of Delaware

Application June 24, 1936, Serial No. 87,923

2 Claims. (Cl. 103—161)

This invention relates to hydraulic machinery, and in particular, to hydraulic pumps or motors of the radial piston type.

One object of this invention is to provide a 5 hydraulic pump or motor having radially reciprocating pistons adapted to engage an eccentrically disposed secondary rotor in a crosshead connection, comprising a cross member mounted on the piston and carrying anti-friction rollers 10 engaging grooves in the secondary rotor, this construction being adapted in operation to cause the pistons to be reciprocated as the rollers travel back and forth in the grooves as the primary and secondary rotors of the pump rotate about 15 their respective axes.

Another object is to provide a hydraulic pump or motor of the type set forth in the preceding paragraph and having a piston and crosshead construction employing a transverse crosshead 20 shaft passing through a bore in the upper portion of the crosshead and having axially spaced rows of needle bearings between it and the crosshead, the opposite ends of the shaft carrying rollers which engage corresponding grooves in the sec- 25 ondary rotor of the pump, thereby eliminating the tendency for the needle bearings to cramp within the crosshead bore by reason of the bending of the crosshead shaft during the operation of the pump or motor at high pressures.

30 In the drawings:

Figure 1 is a vertical longitudinal section through the hydraulic pump or motor of this invention.

Figure 2 is a vertical cross section through the 35 hydraulic pump or motor shown in Figure 1, taken along the line 2—2 of Figure 1.

Figure 3 is an enlarged detail view of a modified piston and crosshead construction differing from that shown in Figure 1.

40 Figure 4 is an enlarged detail view of the piston and crosshead construction and adjacent mechanism as shown in Figure 1.

Figure 5 is an enlarged detail section of the modified construction shown in Figure 3, showing 45 the modified piston, wrist pin and crosshead rollers as applied to the structure shown in Figure 2.

Figure 6 is a cross section taken on the line 6—6 of Figure 3, showing the modified anti-friction bearing construction of Figures 3, 5 and 7 for the crosshead rollers.

Figure 7 is a top plan view of the modified piston and crosshead construction shown in Figure 3, likewise showing the adjacent ridges upon 55 the primary rotor or cylinder barrel.

Figure 8 is a top plan view of the preferred form of piston and crosshead construction as shown in Figures 1, 2 and 4.

Figure 9 is a side elevation of the preferred construction shown in Figure 8.

Figure 10 is a detail view, partly in section, along the line 10—10 of Figure 9, showing the preferred piston and crosshead assembly of Figures 8 and 9.

In general, the pump or motor of this invention consists of a primary rotor, a secondary rotor adapted to rotate upon an axis eccentric to that of the primary rotor, and pistons reciprocable in radial bores in the primary rotor, each piston having at its outer end a shaft mounted in axially spaced rows of anti-friction needle bearings, the shaft having rollers on the ends thereof adapted to travel in tracks or grooves in the secondary rotor. As the primary and secondary rotors rotate about their respective axes, the rollers on the ends of the pistons travel back and forth in their tracks or grooves in the secondary rotor, and a reciprocation is imparted to the pistons. At the same time the rollers do not need to travel back and forth in the tracks at the full operating speed of the pump, but merely travel fast enough to make up for the change in peripheral velocity as the primary and secondary rotors turn on their respective anti-friction bearings. At the same time the piston executes a swinging movement about the anti-friction bearings supporting its crosshead rollers.

Referring to the drawings in detail, Figure 1 shows the hydraulic pump or motor of this invention as consisting of a casing 16 having end plates 11 and 12 secured to the opposite sides thereof, as by the cap screws 13. The end plate 11 is provided with an axial projection 14, having a longitudinal bore 15 provided with transverse bore 16 and 17 for the passage of pressure fluid. Mounted in the longitudinal bore 15 is a pintle 18 having a threaded portion 19 which is engaged by a nut 20. The nut 20 has an incision 21 formed therein, the parts 22 and 23 of the nut 20, on opposite sides thereof, being engaged by the cap screw 24 passing loosely through the hole 25 in the part 22, and having its threads engaging the threaded hole 26 in the part 23. By this means the nut 20 may be adjusted to the desired point, whereupon the tightening of the cap screw 24 causes the parts 22 and 23 to be forced toward one another against the threads of the threaded portion 19, thereby causing the nut 20 to remain firmly locked in position.

tion, without the danger of slippage in either direction.

The purpose of this nut 20 operating upon the threaded portion 19 is for axially or longitudinally adjusting the position of the pindle 18 in order to adjust the clearances of the anti-friction bearings supporting the primary rotor of the pump, as will hereinafter appear. The nut 20 and threaded portions 19 are protected by a cover cap 27 secured to the end of the projecting portion 14 of the end plate 11 by means of the cap screws 28, threaded into the threaded bores 29 thereof.

The pindle 18 is provided with longitudinally disposed pairs of ducts 30 and 31, respectively, one pair of these ducts serving as pressure fluid intake passages and the other pair as fluid discharge passages. The passages 30 and 31 communicate, respectively, with the cut-away portions 32 and 33 in the reduced diameter portion 34 of the pindle. Mounted for rotation on the reduced diameter portion 34 of the pindle 18 is a cylinder barrel or primary rotor 35. For this purpose the pindle portion 34 carries the inner races 36 and 37, respectively, for tapered roller bearings 38 and 39, the outer races 40 and 41 of which are seated in the annular recesses 42 and 43 of the primary rotor 35. The outer races 40 are held in position by the retaining ring 44, secured by means of the set screws 45 to the threaded holes 46 of the primary rotor or cylinder barrel 35. The outer race 41 is held in position by the forwardly projecting flange 47 of the enlargement 48 on the inner end of the drive shaft 49, secured thereto by the set screws 50 engaging the threaded holes 51 in the primary rotor 35.

The inner bearing race 37 is engaged by an end plate 52, secured to the inner end of the pindle 18 by means of the cap screws 53 secured within the threaded holes 54, and with a washer or a plurality of shims 55 arranged therebetween. The inner race 36, however, is loosely mounted so as to slide upon the reduced diameter portion 34 of the pindle 18, and between it and the inwardly projecting flange 56 of the end plate 11 is arranged a sliding ring 57. As a consequence, it will be seen that the turning of the nut 20 upon the threaded portion 19 of the pindle 18 will cause the pindle to move axially. Assuming that this motion is to the left (Figure 1), the end plate 52 will force the inner race 37 to engage the rollers 39. These, in turn, engage the outer race 41 and force it and the primary rotor 35 to the left, together with the opposite outer race 40 and its rollers 38. The inner race 36, however, is prevented from moving to the left because of the presence of the sliding ring 57 engaging the flange 56 on the end plate 11, and consequently 60 remains stationary while the pindle portion 34 slides through it. The result is that the diametrical clearances of the anti-friction bearings 38 and 39 are taken up in this manner so that the bearings may be kept at a tight fit without undue binding or looseness.

The primary rotor is provided with a bore 58 which engages the reduced diameter portion 34 of the pindle 18 with very narrow clearances. The load, however, is taken by the tapered roller 70 bearings 38, whose diametrical clearances may be adjusted to amounts less than the clearance between the primary rotor bore 58 and the pindle portion 34. The latter clearance, therefore, serves merely to permit the free rotation of the 75 cylinder barrel 35 upon the pindle portion 34,

and yet to prevent excessive leakage therebetween.

The cylinder barrel 35 is provided with a plurality of radially disposed cylinder bores 59 having outlet ports 60 communicating at their inner ends with the cut-away portions 32 and 33 in the pindle 18. The cylinder barrel 35 is also provided with lubrication passages 61 for transmitting lubricant therethrough. A similar lubricant passage 62 is provided in the drive shaft 49, the latter having an enlarged portion 63 adapted to support the inner races 64 of double tapered roller bearings 65, having an outer race 66 supported in an annular recess 67 in a projecting flange 68 in the end plate 12. The inner races 65 are held in position by locknuts 69 and 70 having a washer 71 therebetween, these being threaded upon the threaded portion 72 of the drive shaft 49. The annular recess 67 is closed by an end cap 73, secured thereto by the set 20 screws 74 mounted in the threaded holes 75 thereof. An oil retaining ring 76 surrounds the drive shaft 49 in order to prevent leakage along the drive shaft.

Mounted for reciprocation in the cylinder bores 59 are pistons 90. In the preferred form of piston and crosshead construction shown in Figures 1, 2, 4 and 8 to 10, the primary rotor 35 is provided with a ridge 123 having recesses 124 immediately adjacent the tops of the cylinder 30 bores 59. The piston 90 is provided with a top having squared sides 125 and 126, the former being arranged to engage the sides of the recesses 124 so as to be guided thereby. The piston head is provided with a transverse bore 92 adapted to receive the crosshead shaft 93. The latter is rotatably mounted therein by means of the double rows of needle bearings 95 (Figure 10) separated from one another by the annular ridge 121. Upon the ends 94 of the pin 93 are secured rollers 96, these being held in place by the enlarged ends 128. The flattened surfaces 126 on the piston crosshead (Figure 9) are provided with oil grooves 129 (Figure 10) for conveying lubricant to the needle bearings 95.

The crosshead rollers 96 are arranged to engage grooves forming trackways 99 in the secondary rotor halves 100. The latter are joined together by the set screws 101, secured within the threaded holes 102 so that the halves 100 form, in effect, an integral secondary rotor. The latter is provided with annular shoulders 103 adapted to support the inner races 104 of anti-friction tapered roller bearings 105, the outer races 106 being held in position by the retaining rings 107 secured by the set screws 108 within the threaded holes 109 of the shift ring 110. The latter is provided horizontally with diametrically opposed threaded holes 111, within which are mounted the threaded ends 112 of the shift rods 113, the whole being secured in position by the set screws 114. Access to the set screws is obtained through the threaded plugs 115, closing the passages 116 in the casing 10 of the pump (Figure 2).

The shift ring 110 is provided vertically with diametrically opposed flattened portions 117 arranged to engage the correspondingly flattened projections 118 on the interior walls of the pump casing 10. The shift rods 113 pass outwardly through the casing 10 by way of the bores 119. In this manner the shift ring 110 may be moved to and fro, and slidingly supported upon the flattened projections 118 so as to enable it to be placed in an eccentric position relatively to the axis of the pindle 18 and cylinder barrel or pri- 75

mary rotor 35. When the shift ring 110 is so placed the secondary rotor 100 revolves about an axis which is eccentric to that of the primary rotor 35 so that the pistons 88 are caused to 5 reciprocate radially within their cylinder bores 88 by the engagement of their crosshead rollers 96 with the grooves or trackways 98 in the secondary rotor halves 100. At the same time fluid is supplied and removed from the pump by the 10 pintle passages 38 and 31, communicating with the cylinder bores 88 by way of the ports 86 and cut-away portions 32 and 33. Ports 120 are provided at the top and bottom of the shift ring 110, thereby exposing the flattened projections 118 to the action of the oil employed as fluid for the pump.

In the modified construction shown in Figures 3 and 5 to 7, the pistons 88 have flattened portions 81 upon their outer ends. Passing through 20 the flattened portions 81, transverse of each piston, is a bore 92 within which is mounted a wrist pin 93 having reduced diameter portions 94 on its opposite ends. The reduced diameter portions 94 are surrounded by bearings 95, preferably needle bearings, these in turn being surrounded by rollers 96. The wrist pin 93 is held in position within the bore 92 by a set screw 97, threaded into the threaded hole 98. To prevent the rotation of the pistons 88 in their cylinders 25 88, the pistons of the form of pump shown in Figures 3 and 5 to 7, inclusive, are provided with keys 130 secured in recesses 131 by means of set screws 132, and operating in corresponding grooves 133 in the cylinder barrel 88.

30 It will be understood that I desire to comprehend within my invention such modifications as come within the scope of the claims and the invention.

Having thus fully described my invention, what I claim as new and desire to secure by Letters Patent, is:

1. In combination in a hydraulic pump or motor, a primary rotor having cylinder bores, a secondary rotor encircling said primary rotor and having a guideway, pistons with transverse bores therein reciprocable in said cylinder bores, a plurality of spaced annular assemblies of needle bearings mounted in each bore, means for spacing the adjacent ends of said needle bearings in said assemblies apart from each other axially, a piston crosshead shaft rotatably mounted in 10 said needle bearings within each transverse piston bore, and rollers mounted on each crosshead shaft on opposite sides of each piston and engaging said guideway, whereby to eliminate the cramping action of said needle bearings in said 15 assemblies arising from the bending of said crosshead shaft during the operation of said pump or motor.

2. In combination in a hydraulic pump or motor, a primary rotor having cylinder bores, a 20 secondary rotor encircling said primary rotor and having a guideway, pistons with transverse bores therein reciprocable in said cylinder bores, a plurality of spaced annular assemblies of needle bearings mounted in each bore, a piston crosshead shaft rotatably mounted in said needle bearings within each transverse piston bore, an annular spacing member encircling said crosshead shaft for spacing the adjacent ends of said 25 needle bearings in said assemblies apart from each other axially, and rollers mounted on each crosshead shaft on opposite sides of each piston and engaging said guideway, whereby to eliminate the cramping action of said needle bearings 30 in said assemblies arising from the bending of said crosshead shaft during the operation of said 35 pump or motor.

WALTER ERNST.
